UNITED STATES PATENT OFFICE.

FREDERICK T. SNYDER, OF OAK PARK, ILLINOIS, ASSIGNOR, BY MESNE ASSIGNMENTS, TO INTERNATIONAL SEPARATOR COMPANY, OF CHICAGO, ILLINOIS, A CORPORATION OF NEW JERSEY.

MAGNETIC SEPARATOR.

No. 828,304.

Specification of Letters Patent.

Patented June 12, 1906.

Application filed December 6, 1902. Serial No. 134,117.

To all whom it may concern:

Be it known that I, FREDERICK T. SNYDER, a citizen of the United States, residing at Oak Park, in the county of Cook and State of Illinois, have invented a certain new and useful Improvement in Magnetic Separators, (Case No. 4,) of which the following is a full, clear, concise, and exact description, reference being had to the accompanying drawings, forming a part of this specification.

My invention relates to improvements in magnetic separators for the separation of material of all degrees of magnetic permeability.

15 Broadly stated, my invention contemplates the use of a direct-current dynamo or motor for magnetic separation. My invention further includes improvements and novel features adapted to facilitate such use.

20 If the armature of a bipolar dynamo of ordinary construction have a direct electric current passed into it through the brushes and commutator in the usual way, the flow of current around the armature converts it into a magnet having a north pole along an element on one side and a south pole along an element on the opposite side. Passing around the armature in either direction from one pole to the other a neutral element is 25 found at a position somewhere between the north and the south pole. For one pair of poles there are two such neutral elements. If the armature be rotated while the current is passing, the poles remain fixed in position 30 with reference to the points of contact of the brushes on the commutator regardless of the mechanical movement of the armature.

35 My invention contemplates the use of such a rotating armature for the purpose of magnetic separation.

40 If a magnetically-permeable particle be applied to the north pole on the surface of the armature, it is held to the moving surface of the armature and is carried by such moving surface from one pole position to other positions of successively weakening magnetic attractiveness until it reaches the position of the neutral element, when the particle ceases to be held and is free to drop under the influence of gravity or any other force which may 45 be acting, such as centrifugal force due to the rotation of the armature. To secure a magnetic circuit of high average permea-

bility, I provide a field-magnet similar to the field-magnet of an ordinary dynamo.

55 My invention contemplates the use of an armature whose winding may be supplied with current through a commutator or the use of an armature having a short-circuited winding whereby currents set up in the short-circuited winding due to the rotation of the armature in a magnetic field may be utilized to magnetize the armature. In case a commutated winding is employed the brushes may be shifted, and in case a short-circuited 60 winding is employed the winding may be so distributed as to cause shifting of the armature-poles from the position which they would naturally occupy due to field-magnet induction. The position of the poles may be 65 shifted in such a way as to cause a more efficient magnetic separation than could otherwise be attained.

70 While my invention may be applied to a great variety of dynamos and motors by adding a proper means for feeding the materials to be separated and for collecting the separated materials, it is best embodied in a dynamo or motor constructed especially for the purpose.

75 Such a specific embodiment of my invention will be understood by reference to the accompanying drawings, in which—

80 Figure 1 is a view of my improved structure in side elevation. Fig. 2 is a vertical section from front to rear. Fig. 3 is a vertical section in plane of the line A A of Fig. 1. Fig. 4 is a perspective view in detail, showing one end of an armature employing a short-circuited winding. Fig. 5 is a view 85 in detail in perspective of one of the copper plates used for making the short-circuited winding on the armature.

85 Like characters of reference indicate like parts throughout the different figures.

90 I have shown two similar frame-pieces *a*, which are spaced apart and connected by suitable bars *a'* for supporting the operating parts of the machine. The armature (designated as a whole by *b*) is desirably composed 95 of manifold thin disks *b'*, assembled side by side and mounted on a shaft *c*, journaled in suitable bearings in the frame *a* and provided with drive-pulleys *c* and *c'* of different size in order to produce different speeds of rotation 100 of the armature *b*, as may be required.

The armature *b* is provided with longitudinal grooves *b*² for the reception of windings *d*, said grooves separating the periphery of the armature into a series of teeth *b*³, the faces of which are exposed at the periphery of the armature. The teeth *b*³ have sharp edges at the opposite sides of their faces, formed by the sides of the teeth cut on lines which are at an angle of ninety degrees, or thereabout to the plane of their faces.

The windings *d* are intended to fill the grooves *b*² within a short distance of the tops of the grooves, the remaining portions of the grooves being filled by means of non-magnetic material—such, for instance, as strips of wood *d*'—in order to bring the outer surface of the material placed in the grooves *b*² in the curved plane of the face of the teeth *b*³, so that the exterior of the armature *b* may present a smooth continuous surface for the reception of the material to be separated, which is intended to be fed directly theron, as will hereinafter appear.

The armature-winding hereinbefore referred to may be either a commutated winding or a short-circuited winding. In case an ordinary coil-winding is employed I find it desirable to place brushes 77 about one hundred and twenty degrees apart on the periphery of the commutator 8, for the reason hereinafter to be more fully explained. The brushes may be connected with a source of current, such as the generator, (diagrammatically shown at 10,) or may be connected through a variable resistance, whereby the induced currents set up in the windings may be varied in strength.

In case the short-circuited windings are employed they are desirably made to span an arc of one hundred and twenty degrees or thereabout. The short-circuited coils may be formed by utilizing stampings 9, such as illustrated in Fig 5, which may be bent and applied to the armature, as illustrated in Fig. 4, after first being insulated in the usual manner. If the short-circuited winding be put on so as to surround a chord of approximately one hundred and twenty degrees, it is found that on the average the coil is carrying an electric current at a time when it is useful in producing poles in the magnet for a greater length of time than if the windings be put on diametrically. It also permits several windings to be arranged adjacent and without interfering, each winding being more useful than if it had been wound directly across the diameter of the armature. This particular form of winding lends itself to the convenient use of the stamped forms.

60 The armature *b* is intended to be rotated at such speed as may be required for the purposes in hand, a belt *c* leading for this purpose from one or the other of the pulleys *c*' *c*" to a suitable source of power. (Not shown.)

65 The field-magnet is designated as a whole by

c. It may be composed of a series of thin plates *e*' of highly-permeable material, such as steel or iron, held snugly together by end cheek-pieces *e*², having their faces shaped to correspond to the shape of the plates *e*' throughout that portion against which they bear, the said cheek-pieces *e*² being drawn together by means of bolts *f*' *f*", provided with nuts *f*² *f*³, located at opposite ends of the yoke of the magnet, the thin metallic plates *e*² at the free ends of the pole-pieces of the magnet being pressed into close contact by means of screws *g*' *g*", engaged in an arm *g*², fixed to or formed integral with the yoke of the cheek-piece *e*² and extending at its outer end away from the cheek-piece *e*² and then toward the armature-shaft *c*, where it is provided with a hub *g*', embracing the shaft *c* and serving to support the field-magnet in rotary adjustment on the shaft *c*. It is desirable that these cheek-pieces and the supports or connection with the shaft be of non-magnetic material or so arranged as not to afford a path for the magnetic flux. The cheek-pieces, with their arms, are similar at the opposite ends of the magnet *e*, thereby forming a support for the magnet at two widely-separated points on the shaft *c* to hold it accurately in position with respect to the armature. One or both of the cheek-pieces *e*² is provided with a lug *e*³, projecting outwardly therefrom, for the reception of a screw *e*⁴, provided with adjusting-nuts *e*⁵ *e*⁶, one located above lug *e*³ and the other below the lug for the purpose of adjusting the magnet *e* in a circular path 100 around the surface of the armature to shift the position of the poles. The screw *e*⁴ rests on the top of the frame *a*.

The pole-pieces of the magnet *e* are so arranged with respect to the armature *b* as to produce a magnetic field between the pole-pieces of the magnet and the armature. The mounting of the magnet concentric with the shaft of the armature with means for adjusting each at pleasure provides for changing the position of the poles of this field within the limits of the adjusting device, and also for holding the poles stationary so long as the magnet remains in any position to which it may have been adjusted.

The preferred position of the magnet is substantially that shown in the drawings, in which one of its poles is located in proximity to the horizontal plane through the axis of the armature, while the opposite pole of the magnet is located near this pole and above the horizontal plane through the axis of the armature, or it may be in any position in which it does not interfere with the delivery of material to the armature or the removal of the separated portion of said material therefrom. In the form and position shown I find it desirable to bridge the space between the two poles by some suitable non-magnetic material—such, for example, as a piece of 130

wood—the said bridge being designated in the present instance by h . The field-magnet may be energized by an electric current passing from the dynamo (diagrammatically illustrated at e') through the field-coils $e^8 e^9$. A rheostat (shown conventionally at i) serves the purpose of regulating the strength of current passing through the coils, whereby the strength of the poles may be varied.

10 The hopper j , for receiving the material to be fed to the magnetic field, is secured between a pair of standards K , secured to the frame a . The standards K also serve to support at l a feed-spout m , its free end being in proximity to the top of the armature b . This free end of the feed-spout is desirably made of iron or steel, so that it will be attracted by the flux from the armature-teeth. Each tooth then as it passes the end of the spout causes a downward pull thereupon. At the normal rate of rotation of the armature there are a certain given number of downward pulls per minute upon this free end of the feed-spout. The feed-spout is desirably made so that it will vibrate in resonance with the rate of impulses from the armature. Thus upon the normal rotation of the armature a considerable vibratory movement of the feed-spout is set up, which vibratory movement is useful in maintaining an even supply of materials to the armature. A gate n serves to regulate the supply of materials from the mouth of the hopper.

For receiving the material after it has been separated along lines depending upon its magnetic permeability I provide a series of divider-plates, in the present instance four, (designated, respectively, by q, q', q^2 , and q^3), each supported in rocking adjustment from 35 the shaft c of the armature and controlled by rods r, r', r^2 , and r^3 , respectively, leading to crank-arms s, s', s^2 , and s^3 , mounted on the frame a .

Index-pointers t, t', t^2, t^3 are connected, respectively, with the crank-arms $s, s', \&c.$, their free ends passing over graduated scales (designated by u, u', u^2 , and u^3 , respectively) for the purpose of determining to an exact degree the position which any one or more of 50 the dividers shall occupy with respect to the armature and material falling therefrom. Set-screws v, v', v^2 , and v^3 are employed to lock the dividers in adjustment and to release them for the purpose of adjusting. I 55 find it convenient to support hoppers w, w', w^2, w^3, w^4 from the several dividers for the purpose of directing the material into bags or other suitable receptacles which may be connected with their nozzles.

60 For the purpose of leaving the non-magnetic material free to fall after it reaches the point at which it is unsupported by the armature I find it advantageous to cut away the face of the pole-piece of the magnet which 65 rests in proximity to the horizontal plane of

the axis of the armature—for example, as shown at x , Fig. 2—thereby directing its surface more or less away from the face of the armature—as, for example, into or beyond a vertical plane tangent to the armature at this 70 point.

In operation the electromagnet e being energized and the armature b set in motion the material fed directly onto the face of the armature at or near its top will be carried by 75 the armature into the field established between the field-magnet and the armature, those particles of the material which are subject to magnetic influence being held to the surface of the armature, while those which are not subject to magnetic influence will be gradually worked into an outer stratum, and, finally, when the material reaches a horizontal plane through the axis of the armature the particles which are not attracted to the 80 armature will be free to fall, while the magnetic particles will be held to the armature, according to the extent of their magnetic permeability, those which are less permeable falling as they recede from the pole of the armature, while those which are more strongly attracted are carried along nearer to the neutral point, and finally fall from the armature at or before the moment the neutral point is 85 reached. It will be seen that in passing from the feed-point to the point of separation the materials pass through a field of reversed polarity, the particles passing through a neutral point between the pole-pieces of the field-magnet. At this neutral point the magnetic 90 grip upon the permeable particles is for an instant released. This reversal of the magnetic polarity assists in stratifying the two classes of materials before they reach the point of separation. The several dividers 95 will direct the particles, graded according to their magnetic permeabilities, into the hoppers to be collected in bags or other suitable receptacles.

When the armature is wound with the hereinbefore-described commutated winding and supplied with current from an external source or with the short-circuited specially-arranged windings in which electric currents are induced by the rotation of the armature in the 100 field of the magnet, there is a tendency to form secondary poles on the armature, so that the resultant poles used in the separating of magnetic materials will be moved forward in the direction of rotation a distance 105 depending on the relative strength of the poles induced by the field-magnet and the above-mentioned secondary poles. The result of this will be that the magnetic particles will be held on the armature during a 110 greater movement than if the effect of the armature-windings were not present, and consequently there is a better opportunity for 115 separating materials of slightly-differing permeabilities. The amount that the pole can 120

thus be moved down on the armature can be changed in several ways—for instance, by changing the amount of current flowing in the armature, whether this current be that induced by the magnetic force in the field-magnet or be supplied to the armature from an electric generator. It may also be changed by altering the strength of the electric current in the field-magnet or by altering the winding of the armature and the shape of the pole-pieces or by varying the speed of rotation of the armature.

It is desirable that at the time when materials are delivered to the surface of the armature the surface of the armature be moving in the same direction as the materials and at approximately the same speed, with the result that the magnetic attraction does not have to be against the attraction of gravity or friction. At the place where separation is made the magnetic material is already in contact with or closely approaching the surface of the armature, and it is carried on the surface of the armature by magnetic attraction away from the non-magnetic materials.

As many desirable results are obtained by the use of the armature-winding, I call special attention to the desirability of having the winding fill the space between the teeth. I prefer to fill the spaces above the winding flush with the armature-surface with wood or similar material. This filling may also serve to hold the winding in place.

In order to avoid undue heating of the armature, it is desirable to provide ventilating slots y' , passing from the conduit y near the center of the armature.

While I have herein shown and described one particular embodiment of my invention, it will be apparent to those skilled in the art that many modifications and changes might be incorporated therein without departing from the spirit of my invention, and I do not wish to limit myself to the precise disclosure herein set forth, but,

Having described my invention, I claim as new and desire to secure by Letters Patent—

1. In a magnetic separator, the combination with a field-magnet, of a bare armature, a winding on said armature adapted to have a current induced therein by said field-magnet to produce magnetic poles on said armature, and means for feeding materials to be separated into contact with the surface of said armature.

2. In a magnetic separator, the combination with a field-magnet, of a bare armature, a winding on said armature laid in slots therein, means for varying the current in said winding to vary the position of the poles of said armature with respect to said field-magnet, and means for feeding materials between said magnet and said armature and into contact with the bare surface of said armature.

3. In a magnetic separator, the combina-

tion with a field-magnet, of a bare armature having a neutral element, a winding laid in slots in said armature, and means for feeding materials to be separated to the bare surface of said armature.

4. In a magnetic separator, the combination with a bare armature, of a winding laid in slots on said armature carrying electric current, means for rotating said armature, a field-magnet for inducing poles on said armature at points removed from the poles produced by said current, and means for feeding materials into contact with the surface of said armature.

5. In a magnetic separator, the combination with a field-magnet, of an armature in position to be energized by said field-magnet, poles on said field-magnet applied to the armature near together to reduce the width of the weak field near the neutral point between the poles of the field-magnet, and means for feeding materials to be separated into said magnetic field and between the bare surface of said armature and said poles.

6. In a magnetic separator, the combination with an armature, of means for rotating said armature, a field-magnet so arranged as to induce poles on said armature less than one hundred and eighty degrees apart on one side of the armature, and means for feeding materials to be separated between said armature and said field-magnet.

7. In a magnetic separator, the combination with an armature, of means for rotating said armature, a field-magnet, poles on said field-magnet arranged near together one above the other at one side of the armature, and means for feeding materials to be separated between said magnet and said armature.

8. In a magnetic separator, the combination with an armature, of means for rotating said armature, a field-magnet, a pole on said field-magnet at one side of said armature in proximity to the horizontal plane of the axis of the armature, a second pole on said field-magnet at the same side of said armature above said horizontal plane, and means for passing materials to be separated between said field-magnet and said armature.

9. In a magnetic separator, the combination with a toothed armature, of means for rotating said armature, a vibrating feed-spout for feeding materials to be separated to said armature, and a mass of highly-permeable material attached to said spout and adapted to be attracted by the armature-teeth to cause the vibration of said spout.

10. In combination, a field-magnet, an armature, a winding on the armature, so related to the field-magnet as to generate an electric current, said current producing a magnetic field in the armature to act in conjunction with the magnetic field of the field-magnet, means for moving the armature and

means for feeding material to be separated into the field between the field-magnet and the armature.

11. In combination, a field-magnet, a wound armature so related to the field-magnet that a magnetic field is produced having a neutral element on the side of the armature away from the field-magnet, means for moving the armature and means for passing material to be separated through the said magnetic field.

12. In combination, an armature provided with means for carrying electric current, means for moving the armature, a field-magnet for inducing poles in the armature adapted to act in combination with the poles produced by the current in the armature to form resultant poles, means for varying the strength of the field-magnet and hence the position of the resultant poles and means for feeding material to be separated to the armature.

13. In combination, a field-magnet, an armature in position to be energized by the field-magnet, the poles of the field-magnet being applied to the armature so near together as to maintain a magnetic field in proximity to the armature along the interval between the poles of the field-magnet, and means for feeding material to be separated into the magnetic field.

14. In combination, an armature, a field-magnet having its poles brought near together to produce a short magnetic circuit and means for feeding material to be separated between the magnet and armature.

15. In combination, a field-magnet, an armature so related to the field-magnet as to be energized thereby, means for moving the ar-

mature and means for feeding material to be separated between the field-magnet and armature, the poles of the field-magnet being arranged, the one above the horizontal plane of the axis of the armature and the other in proximity to the horizontal plane of the axis of the armature whereby there is first produced a stratifying effect and then a separating effect upon the material passed between the field-magnet and armature.

16. In combination, a field-magnet, an armature in position to be energized by the field-magnet, means for moving the armature, the two poles of the field-magnet being applied at one side to the moving armature, a bridge of non-magnetic material filling the gap between the poles and forming a continuation of the pole-surfaces and means for feeding material to be separated between the field-magnet and armature.

17. In combination, an armature provided with short-circuited windings, a field-magnet for electrically energizing the windings, and means for feeding material to be separated into the field of the armature.

18. In combination, a wound armature provided with teeth having squared corners, the outer surface of the teeth forming a portion of the cylindrical surface of the armature, a field-magnet for magnetically energizing the armature and means for feeding material to be separated onto the armature.

In witness whereof I hereunto subscribe my name this 3d day of December, A. D. 1902.

FREDERICK T. SNYDER.
